US00D574829S

(12) **United States Design Patent**
Shirai et al.

(10) **Patent No.:** **US D574,829 S**
(45) **Date of Patent:** **** Aug. 12, 2008**

(54) **SCANNER**

(75) Inventors: **Masahiro Shirai**, Tokyo (JP); **Kazuhide Sugiyama**, Yokohama (JP); **Teruhiko Kitamura**, Tachikawa (JP)

(73) Assignee: **Canon Denshi Kabushiki Kaisha**, Saitama-Ken (JP)

(**) Term: **14 Years**

(21) Appl. No.: **29/280,651**

(22) Filed: **Jun. 4, 2007**

(30) **Foreign Application Priority Data**

Dec. 5, 2006 (JP) 2006-033501

(51) **LOC (8) Cl.** **14-02**

(52) **U.S. Cl.** **D14/422**

(58) **Field of Classification Search** D14/421-425, D14/462-470, 340, 383-390, 335, 334; D18/36-39, D18/55, 50, 54, 53, 56, 14, 18, 19, 46-49; 355/81, 75, 78; 399/405, 367, 379, 380; 358/496-498, 524, 408, 514, 515, 474, 505; 235/470, 462,43, 482, 483; 400/613, 613.1-613.14, 400/691-694; 101/93.4, 269
